UNITED STATES PATENT OFFICE.

JACOB C. REZNIK, OF BROOKLYN, NEW YORK.

DESIGN FOR CRETONNE.

Application filed July 23, 1923. Serial No. 6,840. Term of patent 7 years.

To all whom it may concern:

Be it known that I, JACOB C. REZNIK, a citizen of the United States, residing at Brooklyn, New York, in the county of Kings and State of New York, have invented a new, original, and ornamental Design for Cretonnes, of which the following is a specification, reference being had to the accompanying drawing, forming part thereof.

The figure is a plan view of a piece of cretonne, showing my new design.

I claim:

The ornamental design for cretonne, as shown.

JACOB C. REZNIK.
